UNITED STATES PATENT OFFICE.

GEORGE W. SHAW, OF TAYLORSVILLE, KENTUCKY, ASSIGNOR OF ONE-HALF
TO THOMAS COLLIER AND JAMES W. WELLS, OF SAME PLACE.

CAR-COUPING.

SPECIFICATION forming part of Letters Patent No. 250,761, dated December 13, 1881.

Application filed March 28, 1881. (Model.)

To all whom it may concern:

Be it known that I, GEORGE W. SHAW, of Taylorville, in the county of Spencer and State of Kentucky, have invented a new and useful Improvement in Car-Couplings, of which the following is a specification.

In the accompanying drawings, Figure 1 is a longitudinal sectional elevation; Fig. 2, a front elevation; Fig. 3, a sectional elevation through the frame-work on the line *x x*, Fig. 1, looking at the back of the plate *F*; Fig. 4, an enlarged sectional plan of plate *J*, which connects the T-shaped lifting-rod and the rigid crank-arm secured in the coupling-pin *E*.

Similar letters of reference indicate corresponding parts.

The object of my invention is to provide an improved car-coupling device which can be operated with ease and certainty from the platforms of passenger-cars or low stock or flat cars, or from the tops of box-cars without going between them, said coupling device being adapted to use the ordinary form of draw-head and draw-bar.

I more particularly describe my invention as follows:

The draw-bar *A* is supported in the frame-work *H* of the car on all sides and slides longitudinally within said frame-work. The said head *A* is divided into two parts, so as to permit the introduction of the head *B'* of the draw-bar bolt *B* into its interior. Said head *B'* being larger than the openings through the front and back ends of the draw-head, it secures the draw-bar bolt *B* within the said head when the two parts of said draw-head *A* are firmly secured by proper bolt-connections. The spring *C* upon the bar *B* acts, between the back shoulder of the recess *A'* and the head *B'*, to hold the coupling-link *D* close to the coupling-pin *E*, as in Fig. 1.

The plate *F* is rigidly attached to the back end of the draw-head *A*, its projecting ends *F'* moving within the grooves or guideways *H'* in the frame-work *H*, and by contact with the forward shoulders of said grooves *H'* causes the draw-head *A* to pull the car without strain upon the draw-bar bolt *B*. Between said plate *F* and the rigid cross-bar *H''* the spring *G* is loosely coiled around the draw-bar *B*, and acts as a

buffer to receive the shock of coupling the cars, it being aided in such action by the forward spring, *O*.

The coupling-pin *E*, when withdrawn from the link *D*, has a bearing in the upper side of the draw-head *A* and in the bracket-bearing *a*, between and in which and the said draw-head the rods *c* are rigidly fastened to guide the vertical movement of the crank-arm *d*, which latter is fastened in the side of the coupling-pin *E*, and has a connection with the plate *J* by its upper arm, *d'*, passing with a sliding fit into a hole drilled through said plate, which connection permits the said arm *d'* to slide within the plate *J* as the draw-head *A*, carrying the coupling-pin *E*, is by any means forced backward. In said plate *J* the foot of the vertically-movable bar *K* is fixed, said bar *K* being guided in bearings *h* on the frame *H*, and having a T or cross head rigidly attached to its upper end, underneath which head *L* the pin *o* on the outer end of crank-arm *N* acts, on the raising of the hand-lever *M* to the perpendicular position shown in dotted lines in Fig. 2, to lift the coupling-pin *E* and uncouple the cars by releasing the link *D* from the draw-head *A*.

A spring-catch may be employed to secure said lever *M* in such perpendicular position and hold the coupling-pin *E* up when it is not desired to couple cars coming in contact with each other.

It is evident that when the draw-bar bolt *B* is pushed backward by the forcible entrance of the coupling *D*, and after the hand-lever *M* is depressed to the horizontal position, the coupling-pin *E* will fall by its own and the super-added weight of the parts *d*, *J*, *K*, and *L*, and secure said link *D*, to couple the cars, as in Fig. 1. Standards *e*, secured to the transverse beam *O* of the frame-work *H*, support the hand-lever *M* at either side in an approximately-horizontal position.

In applying my coupler to box-cars the vertical rod *K*, carrying the cross-head *L*, would be extended upward to permit the lever *M* to be operated relatively to the other parts of my device, as above described, from the roof of said cars.

Instead of using the hand-lever *M*, carrying the crank-arm *N*, and causing the pin *o* on said

arm N to raise the coupling-pin E, as above described, I can use an ordinary hand-wheel, running on a central shaft suitably journaled in the frame-work of the car, and having a pin or roller secured in its face near its circumference, which pin or roller will act under the cross-head L to raise the coupling-pin E in substantially similar manner to the pin o on the arm N, said hand-wheel, with pin or roller attached, being but another form of lever to operate the parts.

Having thus fully described my invention, I claim as new and desire to secure by Letters Patent—

1. The car-coupling pin E, having at the upper part a shoulder, and from thence to the end a diminished diameter, in combination with the bracket a, having a hole in line with the pin-holes of draw-head, as described.

2. The combination, with the pin E, guided at the top in the bracket a, of the crank-arm d, fastened to the side of said pin, the guide-rods e e, and the plate J, connected with a movable bar, K, as and for the purpose specified.

GEORGE WILLIAM SHAW.
